DESIGN FOR A TOOTHBRUSH HOLDER

George J. Evelich, Oakland, Calif.

Application August 13, 1945, Serial No. 121,405

Term of patent 3½ years

(Cl. D4—3)

To all whom it may concern:

Be it known that I, George J. Evelich, a citizen of the United States, residing at Oakland, in the county of Alameda and State of California, have invented a new, original, and ornamental Design for Tooth Brush Holders, of which the following is a specification, reference being had to the accompanying drawing, forming part thereof.

In the drawing:

Fig. 1 is a perspective view of the tooth brush holder showing my new design.

Fig. 2 is a front elevation.

Fig. 3 is a bottom view.

Fig. 4 is an end view.

I claim:

The ornamental design for a tooth brush holder, as shown.

GEORGE J. EVELICH.
